[57] CLAIM

The ornamental design for a modular hanging shelf and
rod unit, substantially as shown.

DESCRIPTION

FIG. 1 is a perspective view of a modular hanging shelf
and rod unit, showing my new design;
FIG. 2 is a front elevational view thereof;
FIG. 3 is a right end elevational view thereof;
FIG. 4 is a rear elevational view thereof; and
FIG. 5 is a bottom plan view thereof.

FIG. 1

FIG. 2

FIG. 3

FIG. 4

FIG. 5
